UNITED STATES PATENT OFFICE.

CLYDE MICHAELIS, OF OMAHA, NEBRASKA.

WINDOW-LIFT.

No. 833,331.

Specification of Letters Patent.

Patented Oct. 16, 1906.

Application filed November 24, 1905. Serial No. 288,894.

To all whom it may concern:

Be it known that I, CLYDE MICHAELIS, a citizen of the United States, residing at Omaha, in the county of Douglas and State 5 of Nebraska, have invented certain new and useful Improvements in Window - Lifts, of which the following is a specification.

My invention relates to improvements in window-lifts; and it consists of the construction, and arrangement of parts described herein, and illustrated by the drawings, wherein—

Figure 1 represents a vertical side view of the invention and a sectional view of a window-sash and window-sill. Fig. 2 represents a front view of the invention; and Fig. 3 is a sectional view of the lifting-lever, bisected on the line *a b* of Fig. 1. Fig. 4 is a perspective view of one of the two side pieces 20 employed in the construction, showing the inner wall thereof to illustrate formation of sleeves. Fig. 5 is a front view of the lifting-block to illustrate form of arms thereof. Fig. 6 is a perspective view of the lifting-block.

The object of the invention is to provide an implement adapted for raising windows which may have become adhesive from presence of paint or varnish at contacting points of the window-sash with the frame or other 30 causes, which may be effective, and by reason of the particular manner of construction may be very cheaply constructed.

The parts consist principally of actuating-levers and a frame therefor, the frame being 35 provided with a hand-rest for sustaining the frame in operative position, together with other parts now to be fully described.

I construct a framework consisting of the side pieces 1 and 2, the base 3, and head-piece 4. The side pieces are held together by rivets therethrough at 5, 6, and 7 and are firmly sustained in their positions by sleeves 9, 10, and 11, constructed, preferably, integral with one of the sides, as side 1. The 45 rivets pass through the sleeves, and upon each of the inner faces of sides 1 and 2 near their front edges I construct the longitudinally-extending groove 13, each groove being formed between flanges 32 and 33. I 50 provide a fulcrum-lever 14, having arms 15 and 16, and between these arms is pivotally mounted at 18 the lifting-lever 17. The base 55 of the fulcrum-lever is pivotally mounted at 8, and the pivot which furnishes this mounting is preferably formed integral with the base of the fulcrum-lever, and since said

pivot has bearings through side pieces 1 and 2 the support is adequate to sustain the strain coming thereon when the levers are operated.

I provide the lifting-block 19, having the arms 20 and 21, and between these arms one end of lifting-lever 17 is pivotally mounted. The lifting-block is provided with the angularly-extending contact-lug 22, reinforced 65 by the bracket 23, integrally constructed therewith. I provide the ball 24, formed, preferably, as a part of the head-piece 4. The side pieces 1 and 2 are provided with the supporting-plates 26, 27, 28, and 29, adapted 70 to support the side pieces 1 and 2 firmly in their relative positions.

In constructing the device economy of labor and material has been observed, and since the sleeves are constructed integral 75 with one of the side pieces said side pieces are sustained relatively parallel in a substantial manner. The lifting-block 19 is provided with lugs 30 and 31, adapted to travel in grooves 13 of sides 1 and 2, the arms 20 80 and 21 being formed convergingly from their bases to their outer ends in a manner to lessen frictional contact with the adjacent flanges 32 and 33 during such travel. I provide the reinforcing-plates 34 and 35 upon 85 the sides, respectively, of side pieces 1 and 2, to furnish additional bearings for the base of the fulcrum-lever pivotally mounted therein.

It will be noted that the construction permits a dropping of the contact-lug to an altitude substantially level with the base 3 and that the fulcrum-lever 14 is adapted to have a movement in common with lever 17, thereby allowing a smooth sliding movement of the parts when raising the block.

Fig. 1 shows a window-sill 36, upon which the invention may be operatively placed adjacent to the lower part of the window-sash 37. The sash is generally provided with a metal-lined recess 38; but in the use of the invention where no such provision has been made a recess is to be angularly formed, as indicated, for engagement therein of contact-lug 22, and as thus arranged the invention may operate as a convenient and effective means 100 105 110 115 for raising windows when the sash has become adhesive.

What I claim as my invention is—

1. A device for the purpose described, having a frame consisting of a base, head-piece, and two adjacently-disposed longitudinally-grooved and rigidly-connected side

pieces; a lifting-block having an angularly-disposed contact-lug formed on its outer face and having a lug formed on each of its ends adapted to have a bearing within the longitudinal grooves of said side pieces; a lifting-lever between said side pieces having one end pivotally connected with said lifting-block; a fulcrum-lever having one end pivotally connected with said lifting-lever the opposite end of said fulcrum-lever being pivotally mounted upon the side pieces of said frame.

2. A device of the character described, comprising a frame having two side pieces, one of said side pieces being provided with angularly-disposed sleeves; said side pieces being adjacently disposed, longitudinally grooved and rigidly connected by rivets passing within said angularly-disposed sleeves; a

lifting-block having an angularly-disposed contact-lug formed on its outer face and having lengthwise-extending lugs formed on each of its ends adapted to have a seating within the longitudinal grooves of said side pieces; a lifting-lever between said side pieces having one end pivotally connected with said lifting-block; a fulcrum-lever having one end pivotally connected with said lifting-lever, the opposite end of said fulcrum-lever being pivotally mounted upon the side pieces of said frame.

In testimony whereof I affix my signature in presence of two witnesses.

CLYDE MICHAELIS.
